United States Patent Office.

JOHN L. TAYLOR, OF NEW YORK, N. Y.

Letters Patent No. 101,941, dated April 12, 1870.

IMPROVEMENT IN SUSPENSORY BANDAGES.

The Schedule referred to in these Letters Patent and making part of the same.

To all whom it may concern:

Be it known that I, JOHN L. TAYLOR, of the city and State of New York, have invented and made an Improvement in Suspensory Bandages; and the following is declared to be a correct description of the same.

Testicle supporters have heretofore been made of a bag with an opening for the penis, said bag having elastic straps permanently connected to or formed with the same.

Supporters of this character are usually worn, and then thrown away because they cannot be washed without injuring or destroying the elastic straps, hence bags of silk, or other expensive material that is the most comfortable for the person, are seldom made use of.

My invention consists in a suspensory bandage made of a bag with the necessary opening for the penis, and connected removably to the elastic waist-belt, and to the strap that passes through between the legs, so that the supporter can be easily detached from the straps for washing, and silk, or other costly material that is most comfortable to the person, can be used and cleansed as often as desired.

In the drawing—

Figure 1 is a perspective view of this supporter as viewed from below the position in which it is worn, and

Figure 2 is a plan of the upper part of the bag and the band attached thereto.

The bag *a* is made of silk net-work, or other suitable material suspended from the head-piece *b*, and

having a binding or hem, *c*, around it in which is the drawing string *d* that is used for giving more or less of a bag-shape to the supporter.

e is an opening of suitable size or shape for the penis.

The waist-band *e* is of elastic material, and I prefer to employ the buckles *f*, so as to adjust the length thereof.

The head-piece *b* is connected removably to the band *e* by the buttons *g*, and button-holes or loops, so that the bag can be easily separated from the band *e*.

The strap *h* passes from the band *e* through a split ring or eye, *i*, that is connected removably to a spring hook or an eye at the center and bottom part of the bag *a*.

This strap *h* passes through between the legs, and is free to accommodate itself to the person or to the movements of the body in consequence of passing freely through the ring *i*, and this ring is unhooked from the bag *a* when the latter requires washing.

I claim as my invention—

The bag *a*, having the head-piece *b* that is connected removably to the band *e*, in combination with the ring or eye *i*, that is removably connected to the bag *a* near the middle at the bottom and through which the strap *h* passes, as and for the purposes specified.

Dated this 4th day of February, A. D. 1870.

JOHN L. TAYLOR.
